UNITED STATES PATENT OFFICE.

EDWARD A. JOHNSTON, OF CHICAGO, ILLINOIS, ASSIGNOR TO INTERNATIONAL HARVESTER COMPANY, OF CHICAGO, ILLINOIS, A CORPORATION OF NEW JERSEY.

CUTTING APPARATUS FOR MOWERS OR REAPERS.

SPECIFICATION forming part of Letters Patent No. 734,714, dated July 28, 1903.

Application filed November 21, 1902. Serial No. 132,279. (No model.)

To all whom it may concern:

Be it known that I, EDWARD A. JOHNSTON, a citizen of the United States, residing at Chicago, county of Cook, State of Illinois, have 5 invented certain new and useful Improvements in Cutting Apparatus for Mowers or Reapers; and I do hereby declare the following to be a full, clear, and exact description of the invention, such as will enable others 10 skilled in the art to which it appertains to make and use the same.

The object in view is to lower the working position of the cutter-bar, so as to bring it as near as possible to the surface of the ground 15 over which it works; and the invention consists in an improved construction of and manner of connecting the shoes to the finger-bar, so that instead of the usual thickness and weight of metal between the shoes and 20 the ground the finger-bar is connected to the shoes at two places, one above and the other below, the principal connection being the one above, and the one below having only sufficient thickness to provide the necessary way 25 for the cutter-bar to slide on.

The improved construction is illustrated in the accompanying drawings, in which—

Figure 1 is a fragmentary plan view of the finger-bar, showing its connection with the 30 usual coupling-yoke. Fig. 2 is a perspective view of the inner shoe. Fig. 3 is a stubble side elevation of the inner shoe, showing the knife-head and knife-head guide in position, also in dotted lines the location of the supplemental wearing-plate. Fig. 4 is a stubble 35 side elevation of the outer shoe, showing the finger-bar and the cutter-bar in the section, also in dotted lines the position of the supplemental wearing-plate. Fig. 5 is a vertical transverse sectional elevation of the finger-bar, showing the construction of the sickle 40 and sickle-clip. Fig. 6 is a vertical longitudinal section on the line 6-6 of Fig. 1.

Referring to the views, *a* denotes the finger-bar. Except in its connection with and manner of securing it to the shoes it is substantially like those in common use. The cutter-bar *b* is also of the ordinary construction and has the usual knife-head *c*, which connects it to the operating-pitman *d*.

The particular construction and manner of securing the inner shoe *e* and outer shoe *f* to the finger-bar, which constitute the essence of the present invention, will be described later on; but their general form and outline 55 are the same as heretofore, and the inner shoe is pivotally connected to the usual yoke *g* by fore-and-aft hinge-pins at *h h*, the yoke itself being sleeved in the outer end of the coupling-bar *i*. Both shoes are provided with 60 the usual wear-plates *j k*, which are shown in full lines in Fig. 1 and in dotted lines in Figs. 3 and 4.

Heretofore the finger-bar has been secured to the upper surface of the shoes only, and in 65 order to make the parts sufficiently strong to meet the requirements it has been necessary to make the underlying parts of the shoes heavy and cumbersome. This had the effect of raising the finger-bar up above the surface 70 of the ground, and of course the cutter-bar was necessarily somewhat above this position. In the present invention the inner shoe has a bottom plate *l* extending from the front upturned end rearward to a point about 75 midway of the width of the finger-bar. As shown in Figs. 2 and 3 of the drawings, this bottom plate is very thin as compared with the corresponding part of the ordinary shoe. In fact, it preferably contains only metal 80 enough to provide the necessary way for the cutter, as it will of course be understood that it and the knife-head *c* slide thereon, being held down in position by the guide *m* overlapping the rear edge of the head, as best 85 shown in Fig. 3.

The rear part *n* of the shoe is disconnected from the bottom plate and raised above its level, as shown in Figs. 2 and 3, and this part of the shoe is connected to the front part by 90 means of a strong vertical yoke-like rib or flange *o*, which extends from near the point of the shoe along its inner edge. On its under side the part *n* of the shoe is rabbeted, as shown at *p*, to receive the upper rear edge 95 of the finger-bar. This edge is preferably plain, as shown in Figs. 1 and 3, as it is desirable to make the upper surface of the finger-bar smooth; but the under surface of the bar is rabbeted along the front edge, as shown 100

at *q* in all the figures, to strengthen it, as the bar is preferably made thinner than usual and so as to receive the bottom plate *l*, flush with the under surface of the rear part, as 5 well as to permit the said plate to be securely fastened in place on the under side of the bar against lateral movement.

The two parts *l* and *n* of the shoe are thus located on opposite sides of the finger-bar 10 and are preferably, though not necessarily, secured thereto by separate fastenings, the part *n* being fastened by the bolt *s* and the plate being fastened by other bolts *t*, which are also preferably the means for securing 15 the knife-head guide *m* to the upper side of the bar.

The outer shoe *f* is constructed with substantially the same thin floor part *u*, extending rearwardly from its front portion, and it 20 has also an overhanging part *v* corresponding in function to the part *n* of the inner shoe and also corresponding thereto in position, except that it extends farther forward so as to actually overlie the rear end of the part *u* 25 and permit the two parts to be secured to the finger-bar by a single fastening-bolt *x* instead of by separate fastenings, as at the other end.

The parts *u* and *v* are fitted to the finger-bar in the same way as the corresponding 30 parts of the inner shoe—that is to say, the part *v* is rabbeted on its under side, as at *w*, and the part *u* fits in the rabbet on the under side of the finger-bar, and the rear part *v* is supported and strengthened from the point 35 or main portion of the shoe by means of the vertical flange *y*.

The construction being as above described it will be readily understood that the finger-bar is thus brought down closer to the ground 40 and that the change from the old construction has been made without sacrificing any of the strength or rigidity of the parts or interfering in any way with the usual adjustability of the wear-plates *j* and *k* through the 45 intermediacy of the ordinary connections *a'* and *b'* for this purpose.

The employment of separate fastenings for the two parts of the inner shoe is of course only a matter of convenience, enabling the 50 provision of the adjustable knife-head guide *m* in position. Obviously, however, the arrangement adopted at the outer end may be employed and the two parts overlapped, so as to permit a single fastening to be employed.

55 Each shoe is practically divided into two parts, the front part consisting of a thin plate and being connected to the under side of the finger-bar, and the rear part, which is the

heavier, being secured to the upper side of the finger-bar on the opposite side from the plate, 60 and the two parts being rigidly secured together by the vertical flanges *o* and *y*, which extend from the upper surface of the front main parts of the shoe and are arched rearwardly over the finger and cutter bar to permit the latter to work freely thereunder. 65

Having thus described my invention, what I claim is—

1. In a cutting apparatus for mowers and reapers, the combination with the finger-bar, 70 of a shoe having a front connection to the under side of the bar, and a rear connection to the upper side of the bar.

2. In a cutting apparatus for mowers and reapers, the combination with the finger-bar, 75 of a transversely-divided shoe, the front part of said shoe being connected to the under side of the finger-bar, and the rear part of the shoe being connected to the upper side of the bar. 80

3. In a cutting apparatus for mowers and reapers, the combination with the finger-bar, 85 of a shoe having a plate extending rearward and secured to the under side of the bar, and an arched bar or rib extending rearward over the cutter-bar, the rear part of the shoe being connected to and supported by said bar or rib, and said rear part of the shoe being secured to the upper side of the finger-bar. 90

4. In a cutting apparatus for mowers and reapers, the combination with the finger-bar, 95 of a divided inner shoe having a rearwardly-extending bottom plate *l* secured to the under side of the finger-bar, an overlying rear part *n* secured to the upper side of the bar, and a vertical bar or rib *o* extending from the upper side of the front part of the shoe rearward above the finger-bar, and supporting and strengthening said rear part *n* of the shoe. 100

5. In a cutting apparatus for mowers and reapers, the combination with the finger-bar, 105 of a divided outer shoe having a rearwardly-extending bottom plate *u*, and a rear part *v* extending forwardly at a higher elevation, the bottom plate being secured to the under side of the finger-bar, and the rear part being secured to the upper side of the bar, and said two parts being secured together by the vertical rib or flange *y*. 110

In testimony whereof I affix my signature in presence of two witnesses.

EDWARD A. JOHNSTON.
